US00D942675S

(12) **United States Design Patent** (10) Patent No.: **US D942,675 S**
(45) Date of Patent: **** Feb. 1, 2022**

(54) **ELECTRONIC CIGARETTE**

(71) Applicant: **HONG KONG IVPS INTERNATIONAL LIMITED**,
Central (HK)

(72) Inventor: **Junwei Ouyang**, Shenzhen (CN)

(73) Assignee: **HONG KONG IVPS INTERNATIONAL LIMITED**,
Central (HK)

(**) Term: **15 Years**

(21) Appl. No.: **29/716,618**

(22) Filed: **Dec. 11, 2019**

(30) **Foreign Application Priority Data**

Nov. 16, 2019 (CN) 201930631996.X

(51) LOC (13) Cl. **27-02**

(52) U.S. Cl.

(57) **CLAIM**

The ornamental design for an electronic cigarette, as shown and described.

DESCRIPTION

FIG. 1 is a perspective View of an electronic cigarette;

FIG. 2 is a front View thereof;

FIG. 3 is a rear View thereof;

FIG. 4 is a top View thereof;

FIG. 5 is a bottom View thereof;

FIG. 6 is a right side View thereof; and,

FIG. 7 is a left side View thereof.

The broken lines in the drawings are for the purpose of illustrating portions of the electronic cigarette that form no part of the claimed design.

1 Claim, 6 Drawing Sheets
